UNITED STATES PATENT OFFICE.

HOWARD W. MORROW, OF PHILLIPSBURG, NEW JERSEY, ASSIGNOR TO INGERSOLL-RAND COMPANY, OF JERSEY CITY, NEW JERSEY, A CORPORATION OF NEW JERSEY.

PIN PULLER.

Application filed January 17, 1923. Serial No. 613,086.

To all whom it may concern:

Be it known that I, HOWARD W. MORROW, a citizen of the United States, and a resident of Phillipsburg, in the county of Warren and State of New Jersey, have invented a certain Pin Puller, of which the following is a specification accompanied by drawings.

This invention relates to pin pullers and particularly to a device of this character adapted to operate in conjunction with a drill sharpening machine to withdraw the pin from a hot drill steel, usually inserted into the bore of the steel to maintain the bore at its proper diameter.

10 Pin pullers of various types are at present used for performing the operation of removing the pin from the bore of the steel, which operation usually requires considerable force because the pin becomes tightly 15 wedged in the hole. Such pin pullers have been provided either as separate machines or as an adjunct to the drill sharpening machine proper, operated independently, either by hand or foot power, or by separate 20 mechanical means.

The primary object of this invention is to enable a pin puller to be conveniently mounted on or built in the stationary portion of a drill steel sharpening machine and 25 operatively connected to a movable member of the drill sharpener so that the pin puller is operated by said movable member of the drill sharpener, instead of by separate or independent manual means. A further object is to simplify and improve the operating 30 mechanism of the pin puller and to permit the same to be automatically locked in inoperative position when not in use, manually operated means adapted to function 35 independently of the movable jaw of the drill sharpener being provided for releasing the operating mechanism when it is desired to use the pin puller.

A still further object is to operate the pin 40 puller by simple and rugged mechanism employing a rack and pinion to effect relative movement of the drill steel and the pin to be removed or withdrawn therefrom. Further 45 objects of the invention will later appear and to all these ends the invention consists of the combination of elements and arrangement of parts substantially as hereinafter

fully described in the following specification and illustrated in the accompanying drawing, in which—

55 Figure 1 is a side elevation partly in section along the line 1—1 of Figure 2 looking in the direction of the arrows showing a portion of a drill sharpener having the pin puller operatively mounted thereon preparatory to pulling a pin from a drill steel;

60 Figure 2 is a top plan view of the pin puller;

65 Figure 3 is a side elevation partly broken away of the pin puller showing the device in the act of completing the pin pulling operation, and

70 Figure 4 is a horizontal sectional view taken on the line 4—4 of Figure 1 looking in the direction of the arrows.

75 Referring to the drawings, the base or cylinder A of a drill sharpener has a movable jaw member or crosshead B carried by the plunger rod C which is adapted to be actuated by a piston (not shown) operating in the base or cylinder.

The pin puller shown in this instance comprises the frame D, which may be secured at the side of the base A in any suitable manner, as by the bolts E. The frame D 80 preferably includes an outer section F, a central filler section G and an inner section H which rests against the base A. A bracket member J is interposed between the sections F and G at the upper portion of the frame 85 and another bracket K is located at the bottom of the frame D. These brackets J and K may be formed integrally with the opposing frame sections F and G or may be secured between the sections in any suitable 90 manner. The bracket J acts as a support for a stationary member shown in the form of an abutment L forming a work support against which a drill steel O is adapted to rest. This abutment may be provided with 95

a recess P for receiving the end of the drill steel O, and also with a groove Q adapted to receive the pin R which has been driven into the end of the steel to maintain the diameter of the central bore S and which pin 100 R is to be removed. The stationary abutment L may be provided with lugs T on its sides adapted to register with similar lugs U formed on the sides of the sections F and

G so that bolts V may pass through these lugs to rigidly secure the stationary abutment L to the frame D.

A toothed reciprocable pin puller rack W having longitudinal side ribs X and teeth Y is mounted to slide horizontally in guides Z between the upper portions of the frame sections F and G, the ribs X traversing the guides Z. This pin puller rack W carries 10 pin engaging means also shown as an abutment a, movable with the rack and formed integrally therewith, and uprising from the end of the rack W adjacent to the stationary abutment L. The abutment a as shown has 15 a groove b aligned with the groove Q of the stationary abutment L and both of the grooves b and Q are adapted to be aligned with the central bore S of the drill steel O, so that the two abutments a and L, the one 20 movable with the rack and the other immovable, may be interposed between the end of the drill steel and the head e of the pin R, the pin R resting in the grooves b and Q.

Suitable operative devices, shown in this 25 instance as rack and pinion mechanism operated by the crosshead, are provided for causing relative movement between the stationary and movable abutments to effect removal of the pin from the steel. The rack 30 and pinion mechanism includes preferably a vertically reciprocable actuating rack d having teeth e and longitudinal ribs f on its opposite sides, the ribs f being adapted to traverse guiding grooves g in the opposing 35 faces of the sections G and H. The teeth e of the rack d intermesh with the pinion h also located between the sections G and H. The ends j and k of the shaft o of the pinion h are supported in the sections G and H, 40 and the end k of this shaft extends to the side F, as shown at p, and is preferably provided with a squared portion q between the sections F and G. A partially formed gear r, having a series of teeth s on a portion 45 of its circumference and a non-toothed portion t is rigidly secured on the squared portion q of the shaft o. The teeth s of the gear r are adapted to mesh with the teeth Y of the pin puller rack W, and as the gear 50 r is fast to the pinion h which in turn meshes with the teeth e of the vertically reciprocable actuating rack d, the pin puller rack W, carrying the movable abutment a will be moved back and forth in accordance with 55 the reciprocatory movements of the actuating rack d. A bearing member u secured on the movable crosshead B of the drill sharpener by bolts v is adapted to engage the top w of the actuating rack d as shown in Figure 1, and will move the rack downward 60 as the crosshead B is lowered to the position shown in Figure 3.

Resilient means are preferably provided for effecting movement of the actuating rack d in the opposite direction. These

means may include a coiled spring x which is adapted to be secured between the projecting top portion y of the rack d and the bracket K which is rigidly located at the base of the guides g, and this spring x is 70 compressed with each downward movement of the crosshead when the pin puller is in operation.

The spring x is provided with suitable guiding means to maintain its alignment 75 and prevent buckling. In this instance the spring surrounds and is guided by a plunger z which is screwed into the projecting portion y, as shown at 1, and a cylinder 2 of substantially the same diameter as the plunger z, screwed into or otherwise suitably fixed to the bracket K, as shown at 3. The plunger z has a smaller diameter portion 4 which is supported and guided in the cylinder 2, and the cylinder 2 is preferably provided with an aperture 5 at one end to maintain atmospheric pressure within the cylinder 2, thus preventing the building up of air cushions which would tend to 80 impede movement of the plunger z, and hence the rack d.

When the crosshead has been lowered and the pin puller rack moved to the position indicated in Figure 3, the gear r will be automatically caught and held against 95 return movement by securing means which may include a pallet or catch 6, secured to a handle 7 and pivoted between the frame sections F and G as shown at 8, so that the weight of the handle 7 normally causes the pallet 6 to bear against the non-toothed surface t of the gear r until the gear r reaches a point where the pallet 6 enters the notch 9 adjacent to the last tooth 10 which will be when the crosshead B has 100 practically descended to the limit of its movement. The pin pulling apparatus is thus held in inoperative position against the force of the spring x with the movable pin engaging means a retracted so that the drill 105 sharpening machine may be freely used for other operations without actuating the pin puller. When it is desired to restore the pin puller to operation, the handle 7 is 110 manually raised slightly, turning the pallet 6 on its axis 8 so that the pallet leaves the tooth 10, whereupon the gear r will be released and the spring x will cause the vertically reciprocable actuating rack d to rise. This reverse movement of the actuating rack 115 d results in corresponding reverse movement of the pinion h, gear r, pin puller rack W and movable abutment a, and the rising movement of the rack d continues until the abutment a assumes its initial position against the stationary abutment L. Obviously, the crosshead B and handle 7 may 120 be raised to permit the pin puller to return to initial position after a pin has been pulled from a steel so that the pin will be carried 125 130

to the front of the machine where it may be more easily removed from the grooves *b* and *Q*, after which the pin puller will be locked in its inoperative position by a succeeding descending movement of the crosshead.

The diameter of the gear *r* is preferably greater than that of the pinion *h* in order to transmit motion which will result in the pin puller rack *W* obtaining a greater length of travel than the distance traveled by the crosshead *B*. This is necessary because in practical use the pins *O* are generally of considerable length while the distance of movement of the crosshead *B* in actual practice is comparatively small. In the present instance, the diameter of the gear *r* is substantially twice that of the pinion *h* which enables the rack *W* to move substantially twice the distance traveled by the crosshead *B* in its raising and lowering movement.

I claim:

1. A pin puller adapted to be associated with a drill sharpening machine having a movable crosshead, said pin puller comprising a stationary member and movable pin engaging means, both adapted to be interposed between the end of a drill steel and the end of a pin inserted in said steel and means for effecting relative movement of said elements to cause the removal of the pin from said steel, said last mentioned means being actuated by movement of the movable crosshead of the sharpening machine, and means independent of the crosshead for retaining said crosshead actuated means in inoperative position.

2. A pin puller adapted to be associated with a drill sharpening machine having a movable crosshead, said pin puller comprising a stationary member and movable pin engaging means, both adapted to be interposed between the end of a drill steel and the end of a pin inserted in said steel, and means for effecting relative movement of said elements to cause the removal of the pin from said steel, said last mentioned means being actuated by movement of the movable crosshead of the sharpening machine, means independent of the crosshead for retaining said crosshead actuated means in inoperative position, and means for causing said crosshead actuated means to return to initial position.

3. A pin puller adapted to be associated with a drill sharpening machine having a movable crosshead, said pin puller including a stationary member and movable pin engaging means adapted to be interposed between the end of a drill steel and the end of a pin inserted in said steel, a pin puller rack and a pinion adapted to effect movement of said pin engaging means to cause the removal of the pin from said steel, said

pin puller rack and pinion being actuated by movement of the movable crosshead of the drill sharpening machine, and means for retaining said pin puller rack and pinion in inoperative position.

4. A pin puller adapted to be associated with a drill sharpening machine having a movable crosshead, said pin puller comprising a plurality of members adapted to be interposed between the end of a drill steel and the end of a pin inserted in said steel, a pin puller rack and pinion adapted to effect relative movement of said members to cause the removal of the pin from said steel, said pin puller rack and pinion being actuated by movement of the movable crosshead of the sharpening machine, means for retaining the movable element in its withdrawn position, and means for causing said movable element to return to initial position.

5. A pin puller adapted to be associated with a drill sharpening machine having a vertically movable crosshead, said pin puller comprising a stationary member and movable pin engaging means adapted to be interposed between the end of a drill steel and the end of a pin inserted in said steel, rack and pinion mechanism actuated by said crosshead for moving said pin engaging means to cause the removal of the pin from the steel, automatic means for retaining said pin engaging means in the moved position, and manually released means for returning said pin engaging means to its initial position.

6. In a pin puller for pulling a pin from an object, a stationary base, a movable crosshead, a stationary abutment against which the object is adapted to rest and a movable abutment adapted to engage the head of the pin, said abutments being mounted on said stationary base, rack and pinion mechanism actuated by the crosshead for moving the movable abutment away from the stationary abutment to cause removal of the pin from the object, and means independent of the crosshead adapted to retain said rack and pinion mechanism in inoperative position.

7. In a pin puller for pulling a pin from an object, a stationary base, a movable crosshead, a stationary abutment against which the object is adapted to rest and a movable abutment adapted to engage the head of the pin, said abutments being mounted on said stationary base, rack and pinion mechanism actuated by the crosshead for moving the movable abutment away from the stationary abutment, means independent of the crosshead adapted to retain said rack and pinion mechanism in inoperative position and means for restoring said rack and pinion mechanism to operative position.

8. In a pin puller for pulling a pin from

an object, a stationary base, a vertically movable crosshead, a stationary abutment against which the object is adapted to rest and a horizontally movable abutment adapted to engage the head of the pin, said abutments being mounted on said stationary base, rack and pinion mechanism actuated by the crosshead for moving the movable abutment away from the stationary abutment, and means adapted to retain said rack and pinion mechanism in inoperative position and to cause the same to return to operative position.

9. A pin puller adaptable for association with a drill sharpening machine having a stationary base and a movable crosshead, said pin puller including a stationary member and movable pin engaging means both adapted to be interposed between the end 15 of a drill steel and the end of a pin to be removed from said steel, rack and pinion mechanism actuated by the crosshead for effecting movement of said pin engaging means to cause the removal of the pin from 20 the steel, and automatic means independent of the crosshead for rendering said rack and pinion mechanism inoperative.

10. A pin puller adaptable for association with a drill sharpening machine having a stationary base and a removable crosshead, said pin puller including a stationary member and movable pin engaging means, both adapted to be interposed between the end 30 of a drill steel and the end of a pin to be removed from said steel, rack and pinion mechanism actuated by the crosshead for effecting movement of said pin engaging means to cause the removal of the pin from the steel, automatic means independent of 35 the crosshead for rendering said rack and pinion mechanism inoperative, and non-automatically actuated means for permitting said rack and pinion mechanism to return to operative position.

45 11. A pin puller adapted to be mounted at the side of a drill sharpening machine having a stationary base and a vertically movable crosshead, said pin puller comprising a stationary member and horizontally movable pin engaging means, both adapted to be interposed between the end of 50 a drill steel and the end of a pin to be removed from said steel, rack and pinion mechanism actuated by the crosshead for effecting movement of said pin engaging means to cause the removal of the pin from the steel, and automatic means independent of 55 the crosshead for retaining said pin engaging means in inoperative position.

60 12. A pin puller adapted to be mounted at the side of a drill sharpening machine having a stationary base and a vertically movable crosshead, said pin puller comprising a stationary member and horizontally movable pin engaging means both

adapted to be interposed between the end of a drill steel and the end of a pin to be removed from said steel, rack and pinion mechanism actuated by the crosshead for effecting movement of said pin engaging means to cause the removal of the pin from the steel, automatic means independent of the crosshead for retaining said pin engaging means in inoperative position and manually released means for permitting said pin engaging means to return to operative position.

13. A pin puller adapted to be mounted at the side of a drill sharpening machine having a stationary base and a movable crosshead, said pin puller comprising a stationary member and movable pin engaging means, both adapted to be interposed between the end of a pin to be removed from said steel, rack and pinion mechanism actuated by the crosshead for effecting movement of said pin engaging means to cause removal of the pin from the steel, automatic means independent of the crosshead for retaining said pin engaging means in the moved position and manually released spring actuated means for causing said movable pin engaging means to return to operative position.

95 14. A pin puller for pulling a pin from an object comprising a stationary base, a movable crosshead, a stationary abutment against which the object is adapted to rest, and movable pin engaging means adapted 100 to engage the head of the pin, said pin engaging means being mounted on a reciprocable pin puller rack, a mutilated gear adapted to engage the teeth of said pin puller rack, a pinion fast to said gear, a reciprocable actuating rack adapted to actuate said pinion, bearing means on the movable crosshead adapted to engage and depress said reciprocable actuating rack when the crosshead is lowered, causing movement of 110 said pin engaging means away from the stationary abutment, automatic means adapted to retain said pin engaging means in inoperative position and non-automatic means for releasing said automatic means 115 to cause the pin engaging means to be returned to its initial operative position when the movable crosshead is raised.

15. A pin puller adaptable for association with a drill sharpening machine having 120 a stationary base and a vertically movable crosshead, said pin puller comprising a stationary abutment against which the object is adapted to rest, and movable pin engaging means adapted to engage the head of the pin, said movable pin engaging means being mounted on a horizontally reciprocable toothed pin puller rack adapted to actuate said pinion, resilient means tending 125 to maintain the reciprocable actuating rack 130

- in its uppermost position, bearing means on the movable crosshead adapted to engage and depress the reciprocable actuating rack when the crosshead is lowered, causing movement of the pin engaging means away from the stationary abutment, a pallet adapted to engage a tooth of the mutilated gear to retain said pin engaging means in inoperative position against said spring and means for releasing said pallet to permit the spring to effect the return of the movable pin engaging means to initial operative position when the movable crosshead is raised.
16. A pin puller for a drill sharpener having a stationary base and a movable cross-head, said pin puller comprising means for holding the drilled steel, means for operatively engaging the pin, and rack and pinion mechanism actuated by the crosshead for effecting movement of said pin engaging means relative to the steel to withdraw the pin from the steel.
17. A pin puller for a drill sharpener having a stationary base and a movable cross-head, said pin puller comprising means for holding the drill steel, means for operatively engaging the pin, rack and pinion mechanism actuated by the crosshead for effecting movement of said pin engaging means relative to the steel to withdraw the pin from the steel, and means adapted to retain said pin puller in inoperative position.
18. A pin puller for a drill sharpener having a stationary base and a movable cross-head, said pin puller comprising means for holding the drill steel, means for operatively engaging the pin, rack and pinion mechanism operated by the crosshead for effecting relative movement of said pin engaging means to withdraw the pin from the steel, means adapted to retain said pin engaging means in inoperative position, and means for restoring said pin engaging means to operative position.
19. A pin puller for a drill sharpener having a stationary base and a movable cross-head, said pin puller comprising means for holding the drill steel, means for operatively engaging the pin, rack and pinion mechanism operated by the crosshead for effecting relative movement of said pin engaging means to withdraw the pin from the steel, and automatic means adapted to retain said pin engaging means in inoperative position.
20. A pin puller for a drill sharpener having a stationary base and a movable cross-head, said pin puller comprising means for holding the drill steel, means for operatively engaging the pin, rack and pinion mechanism operated by the crosshead for effecting relative movement of said pin engaging means to withdraw the pin from the steel, automatic means adapted to retain said pin engaging means in inoperative position, and manually released means for restoring said pin engaging means to operative position.

In testimony whereof I have signed this specification.

HOWARD W. MORROW.
